British Patent No. 1776, dated June 16, 1863,

The addendum referred to in this British Patent and making part of the same.

To all whom it may concern:

Be it known that we, Garrett Smith and Henry Brown of the firm of Smith and Brown, of The City of Philadelphia in the State of Pennsylvania, have invented or produced a new and original ornamental Design for a cooking stove; and we do hereby declare that the following is a full and exact description of the same, reference being had to the accompanying drawings, making a part of this specification.

in which figure 1. represents one of the side plates, figure 2. the upper front plate, and figure 3. one of the like legs of the said stove, having the said ornamental designs applied thereto.

The ornamental parts of the design as applied to the side plates (fig 1) consists of the combined raised configuration A. and the four distinct, raised configurations B. B'. B'' B''' on the large side thereof, the combined raised configuration C. on the smaller door of the oven, the combined raised configurations D. on the panel, the ornamental and recessed side E. of the panel panel, and the two raised configurations F. F' at the ends of the slab G.

The ornamental parts of the Design as applied to the front plate (fig 2) consist of the two distinct, raised configurations H. H. thereon, and the combined, raised configurations I. on each of the doors thereof, the said doors being alike, one only is shown in the drawing. The ornamental parts of the design, as applied to each of the legs, consist of the combined configurations shown as covering its whole face in the drawing fig 3. What we claim herein as our invention or production, and desire to secure by letters patent is. The ornamental configurations described and set forth, as a design for a cooking stove.
